US0D1090088S

(12) **United States Design Patent** (10) **Patent No.:** **US D1,090,088 S**
(45) **Date of Patent:** **** Aug. 26, 2025**

(54) **ARMCHAIR**

(71) Applicant: **Anji Henglin Technology Development Co., Ltd.**, Huzhou (CN)

(72) Inventor: **Jianlin Wang**, Zhejiang (CN)

(73) Assignee: **Anji Henglin Technology Development Co., Ltd.**, Huzhou (CN)

(**) Term: **15 Years**

(21) Appl. No.: **35/516,037**

(22) Filed: **Oct. 26, 2022**

(80) **Hague Agreement Data**

Int. Filing Date: **Oct. 26, 2022**

Int. Reg. No.: **DM/225946**

Int. Reg. Date: **Oct. 26, 2022**

Int. Reg. Pub. Date: **Jan. 20, 2023**
